ABSTRACT

There is provided a fault detecting device for a multiplex signal transmission system which comprises a fault detecting circuit, whereby when a fault occurs in the level signal line for sending load actuating command signals in a multiplex signal transmission system operated in a time-shared manner, the fault detecting circuit generates a signal for preventing the actuation of the loads due to the fault.

FAULT DETECTING DEVICE FOR MULTIPLEX SIGNAL TRANSMISSION SYSTEM

BACKGROUND OF THE INVENTION

FIELD OF THE INVENTION

The present invention relates to a fault detecting device for a multiplex signal transmission system comprising a transmitter and a receiver and employing a multiplex communication method based on time-sharing.

SUMMARY OF THE INVENTION

It is the object of the present invention to provide a fault detecting device for a multiplex signal transmission system which detects the occurrence of a fault in the level signal line for sending load actuating command signals and prevents the actuation of the loads due to the fault.

A remarkable advantage of the device of the present invention is the use of a fault detecting circuit in a multiplex signal transmission system comprising a transmitter and a receiver and employing a multiplex communication method based on time-sharing with the result that when a fault occurs in the level signal line for sending load actuating command signals, the fault is detected to prevent the actuation of all the loads due to the fault.

BRIEF DESCRIPTION OF THE DRAWING

FIG. 1 is a block diagram showing an embodiment of a fault detecting device for a multiplex signal transmission system according to the present invention.

FIGS. 2A to 2J are waveform diagrams useful for explaining the operation of a time-sharing multiplex signal transmission system incorporating the detecting device according to the invention.

FIG. 3 is a block diagram showing the oscillator and the counting blocks shown in FIG. 1.

FIGS. 4A to 4M are operating characteristic diagrams of the scale-of-10 counter used in the first counting block shown in FIG. 3.

FIG. 5 is an electric circuit diagram of the reset pulse generating circuit shown in FIG. 3.

FIGS. 6A and 6B are input and output characteristic diagrams of the reset pulse generating circuit shown in FIG. 5.

FIG. 7 is an electric circuit diagram showing in detail the internal circuit of the first counting block shown in FIG. 3.

FIG. 8 is a block diagram showing a part of the combining block shown in FIG. 1.

FIG. 9 is an electric circuit diagram of the whole combining block shown in FIG. 1.

FIG. 10 is a block diagram of the second counting block shown in FIG. 1.

FIG. 11 is an electric circuit diagram showing a part of the restoring block shown in FIG. 1.

FIG. 12 is an electric circuit diagram of the whole restoring block shown in FIG. 1.

FIG. 13 is a block diagram of the multiplex signal transmission system incorporating two receivers.

FIG. 14 is an electric circuit diagram showing an embodiment of the fault detecting circuit used in the device of this invention.

FIGS. 15A to 15C are waveform diagrams useful for explaining the operation of the fault detecting circuit shown in FIG. 14.

FIG. 16 is an electric circuit diagram showing another embodiment of the fault detecting circuit in the device of this invention.

FIGS. 17A to 17I are waveform diagrams useful for explaining the operation of the fault detecting circuit shown in FIG. 16.

DESCRIPTION OF THE PREFERRED EMBODIMENTS

10 The present invention will be described hereunder with reference to the illustrated embodiments.

An embodiment of a time-sharing multiplex signal transmission system incorporating the device according to the present invention will be described first with reference to FIGS. 1 to 13.

15 In FIG. 1, which shows a block diagram of the overall device according to the invention, a transmitter 1 is constituted of a first counting block 2, a combining block 3 and an oscillator 110, while a receiver 4 consists of a second counting block 5 and a restoring block 6, and a power source 7 may be, for example, an accumulator.

20 The general description of the time-sharing multiplex signal transmission system incorporating the device according to the present invention shown in FIG. 1, will now be described by reference to the waveforms shown in FIGS. 2A to 2J. The time base indicated at 101 in FIG. 2D is divided into equal periods, each comprising smaller intervals 00, 01, 02, . . . , 99,

25 and signals to be transmitted to the receiving end are allotted to the intervals. The receiver discriminates whether the intervals contain the corresponding signals or not and picks up the predetermined ones of the signals only when they are contained in the respective intervals. This time-sharing process is performed on the basis of a synchronous signal indicated at 123 in FIG.

30 2B and delivered from the first counting block 2 and a timing signal 122 indicated at 122 in FIG. 2A, through the provision of the scale-of-10 counters in the counting blocks 2 and 5 respectively of the transmitter 1 and the receiver 4. These scale-of-10 counters generate an address signal corresponding to the thus defined intervals, i.e. time-shared intervals. The signals to be transmitted are combined together through the combining block 3 to produce a level signal indicated at 124 in FIG.

35 2C, which is transmitted from the combining block 3. Therefore, the signal transmission between the transmitter 1 and the receiver 4 is through three lines, i.e. line L₁ for the synchronous signal 123, line L₂ for the timing signal 122 and line L₃ for the level signal 124, while two additional lines L₄ and L₅ are provided therebetween for the purpose of power feeding. The synchronous signal 123 in which a period corresponding in time to the time-shared interval 00 has a lower level,

40 is transmitted from the counting block 2 to the counting block 5. A reset signal 151 shown in FIG. 2H is obtained from a signal indicated at 161 in FIG. 2G in which a period corresponding to the time-shared interval 00 has a higher level. And the reset signal 151 resets frequency dividers and the scale-of-10 counters in

45 the counting blocks 2 and 5. Each time-shared interval is superseded by the succeeding one every second period of the timing signal 122. Thus, the scale-of-10 counters provided in the counting blocks 2 and 5 are operated all in synchronism. The level signal 124 to be transmitted from the transmitter 1 to the receiver 4 is obtained by passing, i.e. taking a logical product of,

50 three signals; a predetermined input signal to be trans-

mitted, an address signal from the scale-of-10 counter containing addresses indicative of the numeral-pairs (such as 02 or 04) of the time-shared intervals into which the input signal is allotted, and a strobe signal indicated at 181 in FIG. 2E; through an AND gate. The level signal 124 shows a case where a signal to be transmitted is superposed on the addresses in the time-shared intervals indicated by the numeral-pairs 01 and 02. This level signal 124 is then restored through the restoring block 6 in the receiver 4 in the manner described below. The initial state is established by applying the reset signal 151 shown in FIG. 2H to the reset input of a first memory circuit during the time-shared interval 00. Then, an output signal which is the logical product of the address signal appearing in the predetermined time-shared intervals and the level signal 124, is applied to the set input of the first memory circuit. Therefore, if an AND signal is applied to the set input the initial state of the memory circuit is cleared, while the initial state is maintained if there is no input to the memory circuit. Namely, the state of the first memory circuit is determined depending upon whether there is a level signal in respective time-shared intervals or not. The state is again cleared when the following time-shared interval 00 has been reached and it is necessary to transfer the content of the first memory to a second memory circuit before the former is cleared. This transfer operation is performed during the time-shared interval 99 by applying a transfer signal 171 shown in FIG. 2F, which is the logical product or AND of the interval 99 and the strobe signal 181 in FIG. 2E, to a gate which controls the transmission of the signal between the first and second memories. If in signal 124 a predetermined signal is in the interval 01 (or has a lower level in the interval), the content of the first memory is continuously fed to and stored in the second memory during the duration of a signal 191 shown in FIG. 2I from the time-shared interval 99 in a period to the interval 99 in the next period. If, on the other hand, in the signal 124 a predetermined signal is in the interval 02, the transfer of the content takes place in a similar manner, but during the duration of a signal 192 shown in FIG. 2J with a delay of one period with respect to the signal 191. Therefore, if in the level signal 124 a predetermined signal appears in every interval 01, the signal 191 will last without interruption from the interval 99 shown in FIG. 2I onward.

Now, the signal transmission according to the time-sharing system will be described with a detailed description of the circuit constitutions of the essential blocks. FIG. 3 shows the constitutions of the oscillator 110 and the first counting block 2 in the transmitter 1. The oscillator 110 may be constituted of a tuning fork and quartz or have resort to a capacitor-resistor compensated feedback method. In the first counting block 2, the n -th output 121 and $(n-1)$ -th output 122 (timing signal shown in FIG. 2A) of the n -th stage of a frequency divider circuit 120 are applied to a logic circuit 180, which takes the NAND of the outputs. The output of the NAND circuit 180 is then fed to an inverting gate 182, which in turn delivers the strobe signal 181. The strobe signal 181 is used to prevent the interference of the signals indicative of the time-shared intervals in transmission and reception. The logic circuit 180 may be substituted by an OR ELSE circuit which takes the exclusive logic sum of the signals 121 and 122. Reference numerals 130 and 140 indicate scale-of-10 count-

ers. The scale-of-10 counter 130 must be a device which delivers at its output terminals 130-0 to 130-9 output signals having waveforms as shown in FIG. 4. This requirement can be satisfied by using the well known MOS IC CD4017D manufactured by RCA or by a combination of suitable gates. FIG. 4A shows an output signal 121 frequency divided by the frequency divider circuit 120, FIG. 4B shows a reset signal 151 which is an output of a reset pulse generating circuit 150 described below, FIGS. 4C to 4L show signals delivered respectively from the output terminals 130-0 to 130-9 of the scale-of-10 counter 130, and FIG. 4M shows an output signal 131 from the counter 130. The signal 131 from the counter 130 indicating the digit of the first place of the numeral-pair representing the time-shared interval, is applied to the scale-of-10 counter 140 which delivers an output signal indicating the digit of the second place of the same numeral-pair. The scale-of-10 counter 140 operates in the same manner as the counter 130. The signals derived respectively from the output terminals 130-0 and 140-0 of the counters 130 and 140 are fed to an AND gate 160, the output of which is then applied to an inverting gate 162 to obtain a synchronous signal 123 at its output terminal. The reset pulse generating circuit 150 receives the output signal 161 of the AND gate 160 as its input signal, and an embodiment of the circuit 150 is illustrated in FIG. 5. In FIG. 5, the reset pulse generating circuit 150 comprises an AND gate 150a, inverting gates 150b to 150d, an input terminal 150e and an output terminal 150f. When the output signal 161 of the AND gate 160 whose waveform is shown in FIG. 6A (identical with that shown in FIG. 2G), is applied to the input terminal 150e, then at the output terminal 150f appears the reset signal 151 shown in FIG. 6B (identical with that shown in FIG. 2H). The reset signal 151 as the output of the reset pulse generating circuit 150 is applied to the reset terminals of the frequency divider circuit 120 and the scale-of-10 counters 130, 140, respectively.

It is assumed in the following description that the frequency divider circuit 120 has a dividing factor equal to half a bit and that the $(n-1)$ -th output of the circuit 120, i.e. output of the oscillator 110, is used as the timing signal 122. CD4217D

FIG. 7 shows a concrete embodiment of a circuit shown in a block diagram in FIG. 3. In FIG. 7, the descriptions of the already mentioned circuit elements are abridged. The oscillator 110 has a well known constitution comprising inverting gates 110a, 110b and 110c, a resistor 110d and a capacitor 110e. The frequency divider 120 comprises a flip-flop 120a and an inverting gate. The scale-of-10 counter 130 is the above-mentioned, well-known MOS IC CD4217D by RCA, which comprises D flip-flops 130a to 130e, negative logic AND gates 130f to 130p, a NOR gate 130q and an inverting gate 130r. The scale-of-10 counter 140 has the same constitution and operates in the same manner as the counter 130. The logic circuit 180 is a NAND gate 180a. An AND gate 170 and an inverting gate 152 in the unit shown in FIG. 7 are useful only where the unit is used for the second counting block 5 in the receiver 4 but useless where the unit is used for the first counting block 2 in the transmitter 1. These elements are incorporated together with other circuit elements in a single IC unit or package and, therefore, if the unit is used for the first counting block 2 of the

transmitter 1, the AND gate 170 and the inverting gate 152 are left out of electrical connection.

FIG. 8 shows a part of the combining block 3 of the transmitter 1, having a constitution for one channel associated with one address. The terminals 211 and 212 are connected respectively with the selected one of the terminals 130-0 to 130-9 of the scale-of-10 counter 130 and the selected one of the terminals 140-0 to 140-9 of the scale-of-10 counter 140 so as to obtain an address representative of a predetermined time-shared interval. For example, in order to obtain an address indicating the time-shared interval 13, it is only necessary to connect the terminal 211 with the output terminal 140-1 of the counter 140 associated with the digit of the second place of the numeral-pair representing the time-shared interval and the terminal 212 with the output terminal 130-3 of the counter 130 associated with the digit of the first place of the numeral-pair representing the time-shared interval. Such connections are represented for simplicity's sake by a dashed line in FIG. 1 connecting the first counting block 2 with the combining block 3. A terminal 220 is an input terminal which receives a signal transmitted from the transmitter 1 to the receiver 4 and an inverting gate 221 is provided to deliver the inversion of the input signal. The NAND gate 240 takes the NAND of the signals applied to the terminals 211 and 212 and the signal delivered from the inverting gate 221. Namely, the gate 240 delivers a low-leveled, "0" signal only when there are applied to the gate 240 a predetermined address signal and an input signal corresponding to the address. The output of the NAND gate 240 together with the outputs of the other NAND gates similar to the NAND gate 240 which are associated with the other addresses, is applied to a NAND gate 250. This state is, for example, illustrated in FIG. 9. A NAND gate 260 takes the NAND of the output signal from the NAND gate 250 and the strobe signal 181 and delivers the level signal 124 to the line L_3 . The combining block 3 shown in FIG. 9 is adapted for receiving ten inputs, i.e. ten channels, corresponding to ten addresses. However, if, as described later, the receiver 4 has eight input terminals, only eight channels out of ten are used for signal transmission. The selection of any address corresponding to each of the time-shared intervals 00 to 99 can be made by appropriately combining the outputs of the scale-of-10 counters 130 and 140. The number of channels for signal transmission in this embodiment is not limited to eight but may be increased up to 98, if need be, since there are ninety-eight time-shared intervals 01 to 98.

As described above, in signal transmission, any one of the addresses corresponding to the time-shared intervals 00 to 99 can be arbitrarily selected by means of the counting block 2 and the combining block 3.

Now, the constitution and the operation of the receiver 4 will be described. The receiver 4 comprises the restoring block 6 and the second counting block 5 similar to the counting block 2 shown in FIG. 7 but with a somewhat different connection. FIG. 10 illustrates in detail the constitution of the counting block 5 for use in the receiver 4. The frequency divider circuit 120' is actuated by the timing signal 122 which is received from the first counting block 2 in the transmitter 1 through the line L_2 . The reset pulse generating circuit 150' receives the output of an inverting gate 152 (see FIG. 7) which inverts the synchronous signal 123 fed through the line L_1 . The signals appearing at the output

terminal 130'-9 of a scale-of-10 counter 130' associated with the digit of the first place of the numeral-pair representing the time-shared interval and at the output terminal 140'-9 of a scale-of-10 counter 140' associated with the digit of the second place of the same numeral-pair, and the strobe signal 181 are applied to an AND gate 170 to produce the transfer signal 171. With the circuit configuration described above, the scale-of-10 counters 130' and 140' operate in synchronism with the transmitting end.

The circuit of the second counting block 5 in the receiver 4 is the same as that of the first counting block 2 in the transmitter 1 in FIG. 7, but the NAND gate 160 and the inverting gate 162 shown in FIG. 7 are unnecessary for the operation of the second counting block 5 and they are omitted in the circuit shown in FIG. 10. The frequency divider circuit 120', the scale-of-10 counters 130' and 140', the reset pulse generating circuit 150' and the logic circuit 180' of the second counting block 5 in the receiver 4 have the same constitutions and operate in the same manner as those of the first counting block 2 in the transmitter 1 in FIG. 7.

FIG. 11 shows the electrical connection of one of the constituents, i.e. equivalent components, of the restoring block 6. NAND gates 310 and 320 form a set-reset type flip-flop serving as a first memory circuit. NAND gates 360 and 370 also form a set-reset type flip-flop serving as a second memory circuit. Numeral 400 designates a fault detecting circuit. This unit receives the strobe signal 181 and the transfer signal 171 from the second counting block 5 shown in FIG. 10 and has terminals 211' and 212' which are adapted to receive an address signal representing a time-shared interval. For example, if the terminals 211' and 212' are connected respectively with the output terminal 140'-1 of the scale-of-10 counter 140' and the output terminal 130'-3 of the scale-of-10 counter 130', an address signal indicative of the time-shared interval 13 is introduced to the unit. These connections are represented for simplicity's sake by a dashed line between the second counting block 5 and the restoring block 6 in FIG. 1. The operation of the unit is as follows. The first memory circuit assumes its initial state upon reception of the reset signal 151 from the second counting block 5 to maintain the output terminal 311 at a higher level and the output terminal 321 at a lower level and this state continues after the reset signal 151 has ceased. If, for example, the address signal representing the interval 13 is applied from the counters 130' and 140' respectively to the terminals 211' and 212' while at the same time the level signal 124 applied to the unit through the line L_3 has the higher level allocated to the corresponding interval 13, then the terminal 331 is maintained at the higher level. If the strobe signal 181 assumes the higher level in response to the interval 13, the NAND gate 330 is enabled to maintain its output terminal 332 at the lower level. Accordingly, the state of the first memory circuit is changed so that the output terminals 321 and 311 are maintained respectively at the higher and lower level. And this state is maintained even after the time-shared interval 13 has passed away, since both the signal at the output terminal 332 and the reset signal 151 assume the higher level. The levels at the terminals 321 and 311 are transferred respectively to the NAND gates 370 and 360 forming the second memory circuit through the NAND gates 340 and 350 opened by the transfer signal 171 generated during the

time-shared interval 99. Namely, the very signal appearing at the terminal 311 when the transfer signal 171 is on the point of being generated, appears at the output terminal 361. This is true also for the terminals 321 and 371. The state of the second memory circuit is maintained until the next pulse of the transfer signal 171 has arrived.

FIG. 12 illustrates an exemplary circuit diagram of the restoring block 6 comprising eight equivalent units, one of which is illustrated in FIG. 10. Here, the fault detecting circuit 400 is not shown. In the constitution of the restoring block 6 shown in FIG. 12, the reset signal 151, the level signal 124, the strobe signal 181 and the transfer signal 171 are applied respectively with the input busses common to the eight units.

A plurality of receivers may be introduced in place of one and in this case the time-shared intervals in use have to be allocated appropriately to the plural receivers. FIG. 13 shows a case where two receivers are connected with one transmitter. This is usual, for example, with the application to an automobile in which it is required to controllably energize the front search light and the tail lamps by a manual switch actuated by the driver. In such a case, the transmitter is placed within the driver's reach and the two receivers are placed within the engine room and the trunk room and the wired OR method using DTL may be resorted to.

The fault detecting circuit 400 used in the above-described multiplex signal transmission system to forcibly prevent the actuation of the loads under fault conditions resulting from the grounding of the level signal line, that is, under abnormal conditions where the loads tend to be actuated irrespective of the presence or absence of commands, will now be described with reference to FIG. 14. The fault detecting circuit shown in FIG. 14 is adapted for incorporation in the previously described restoring block 6 and it receives the transmitted level signal 124 as well as the actuation command signal restored in the restoring block 6 and applied to the terminal 361 shown in FIG. 11. In FIG. 14, the letter R designates a resistor, C a capacitor, 410 an inverting gate, 420 a NOR gate, 430 a load.

When the level signal 124 which becomes abnormal at a point *a* in FIG. 15A by the grounding of the level signal line is introduced to the fault detecting circuit 400, the waveform shown in FIG. 15B is generated at a terminal RC by the integrator circuit comprising the capacitor C and the resistor R and the waveform shown in FIG. 15C appears at an output terminal 421 of the inverting gate 410. In other words, the "1" level signal appears upon the occurrence of the fault at the point *a*. When this occurs, irrespective of the signal state of the actuation command signal for actuating the load 430 which is applied to the terminal 361, a "0" signal appears at the output of the NOR gate 420 to forcibly prevent the actuation of the load 430. When the level signal 124 returns to the normal state, the signal at the output terminal 421 of the inverting gate 410 changes to "0" and therefore the inverted signal of the applied signal at the terminal 361 appears at the output of the NOR gate 420. This signal determines whether the load 430 should be actuated or not.

FIG. 16 illustrates another embodiment of the fault detecting circuit in the device of this invention which includes memory circuits. The fault detecting circuit of FIG. 16 receives, for example, the multiplex communication level signal 124 as well as the reset signal 151

and the transfer signal 171 generated by the circuit shown in FIG. 10 and it also receives as in the embodiment of FIG. 3 the load actuating command signal applied to the terminal 361.

When the level signal 124 which becomes abnormal by the grounding of the level signal line at the point *a* in FIG. 17A is applied to the circuit, it is inverted by an inverting gate 410a to produce at a terminal 411 the waveform shown in FIG. 17B. This waveform is applied to the input 411 of a set-reset type flip-flop memory circuit comprising NAND gates 410c and 410d. The other input of this flip-flop receives the inverted waveform of the reset signal 151 shown in FIG. 17C. Consequently, the waveforms shown in FIGS. 17E and 17F appear respectively at flip-flop output terminals 412 and 413. The logical products of these output waveforms with the transfer signal 171 shown in FIG. 17D are produced by NAND gates 410e and 410f so that the waveforms shown in FIGS. 17G and 17H are produced at their respective output terminals 414 and 415. These output waveforms are applied to the respective inputs of the second stage set-reset type flip-flop memory circuit comprising NAND gates 410g and 410h to produce the waveform shown in FIG. 17I at a flip-flop output terminal 421. In other words, if the level signal 124 becomes abnormal at the point *a* in FIG. 17A, then the abnormal level signal which changes to "1" upon the arrival of the first "1" level pulse of the transfer signal 171 shown in FIG. 17D appears at the output terminal 421 and this abnormal signal is applied to the NOR gate 420. When this abnormal "1" level signal is present at the NOR gate 420, irrespective of the introduction of the actuation command signal for actuating the load 430 applied to the terminal 361, the signal at the output of the NOR gate 420 changes to "0" to forcibly prevent the actuation of the load 430. In this way, when a fault condition occurs as a result of the grounding of the level signal line, any erroneous operation of the loads can be prevented. Further, the above-mentioned flip-flops are not limited to the set-reset type, but they may be of the J-K type or the D-type.

I claim:

1. In a multiplex signal transmission system comprising a transmitter for generating a synchronous signal, a timing signal and a level signal having information to be transmitted superposed on the designated addresses, and a receiver including signal generating means for receiving said signals to generate a reset signal and a transfer signal, and restoring means for receiving said reset signal, said transfer signal and said level signal to generate an actuation signal, a fault detecting circuit comprising detecting means for generating a signal by detecting the fact that said level signal has superposed information on all the addresses, and means connected to said restoring means to block said actuation signal upon the generation of said detected signal.

2. A fault detecting circuit according to claim 1, wherein said detecting means comprises an integrator circuit.

3. A fault detecting circuit according to claim 1, wherein said detecting means comprises a first flip-flop circuit having a first terminal for receiving said level signal and a second terminal for receiving said reset signal, two logic circuits each thereof having a first input terminal connected to said first flip-flop circuit and a second input terminal for receiving said transfer signal, and a second flip-flop circuit connected to said logic circuits.
